UNITED STATES PATENT OFFICE.

CARL ALRIK HULT AND OSCAR WALFRID HULT, OF STOCKHOLM, SWEDEN.

GOVERNING DEVICE FOR EXPLOSION OR COMBUSTION MOTORS.

1,103,290.

Specification of Letters Patent.

Patented July 14, 1914.

Application filed November 23, 1912. Serial No. 733,068.

To all whom it may concern:

Be it known that we, CARL ALRIK HULT and OSCAR WALFRID HULT, subjects of the King of Sweden, and residents of 1 Inedalsgatan, Stockholm, in the Kingdom of Sweden, have invented certain new and useful Improvements in Governing Devices for Explosion or Combustion Motors, of which the following is a specification, reference being made to the accompanying drawings.

The present invention relates to a governing device for such explosion or combustion motors as have a motive fluid pump, the piston of which is caused to perform its functional movement by a part driven by the motor. A governing device carried out in accordance with the present invention is characterized mainly by the fact that the said part acting on the piston is movable toward and from the center line of the motor shaft and connected with a speed governor, mounted on the said shaft, in such a manner, that when the governor makes a deflection in consequence of an increase of speed in the motor, the part acting on the piston pump approaches the said center line, in consequence of which the functional movement of the pump piston is diminished, so that a smaller quantity of motive fluid is fed into the motor, the speed of which is thus reduced to the normal.

In the accompanying drawing are shown by way of example various forms of this invention.

Figures 1, 2, 3, and 4 show the one of the forms, partly in section and partly viewed from one side, while Figs. 5 and 6 show the other form, partly viewed from the side and partly in section. Fig. 7 shows a modification of a detail and Fig. 8 another modification.

In the web 1 of the fly wheel 2 of the motor is journaled a pivot 3, which on the part situated outside the web carries a governor weight 4, connected with a spring 5 fixed to the web, the tension of which spring 5 is adjustable and counteracts the action of centrifugal force on the governor weight, the deflection of which weight is thereby kept within suitable limits. On its end situated inside the web 1 the pivot 3 carries an arm 6 which is provided with a preferably annular extension 10 having formed thereon a shoulder 7, which shoulder once during every revolution of the motor shaft impinges on the pump piston 8, which projects from

the housing of the motive fluid pump, whereby the piston becomes lifted, driving a certain quantity of motive fluid or liquid to the motor cylinder. The return movement of the piston is brought about in the usual manner by a spring 9 placed in the housing of the pump. That part of the arm 6 which is provided with the shoulder 7 may suitably be in the form of a ring 10, surrounding the motor shaft. When the governor weight 4 in consequence of an increase of speed of the motor is deflected, *i. e.* turns round the axis of rotation of the pivot 3, the shoulder 7, as will be seen from Fig. 3, is moved toward the motor shaft. As a consequence of this the distance which the shoulder moves the pump piston 8 into its casing is less than when the motor is running with its normal speed, whence a smaller quantity of motive fluid is fed into the motor cylinder, so that the motor reassumes its normal speed. The greater the increase of speed, *i. e.* the greater the deflection of the governing weight, the smaller the distance which the shoulder moves the pump piston, *i. e.* the less the feeding in of the motive fluid.

As in the arrangement shown in Figs. 1 to 3 also in the arrangement shown in Figs. 5 and 6 and which, as far as the parts 1 to 6 are concerned, is in the main similar to the previous arrangement, the arm 6 is provided with a ring 11 surrounding the motor shaft. The said ring 11, which is eccentric relatively to the motor shaft, is, however, not provided with any shoulder, but is embraced by a strap 12, provided with an arm 13, the free end of which arm, which end is connected with a guiding link 14 mounted on a fixed part of the machine, acts on the pump piston 8, or on a part connected with the same. The arm 13 may also be articulated to a part longitudinally displaceable in the guide 15. The eccentric strap 10 may be connected with a rocking arm of the kind commonly employed for obtaining a rapid injection. The part 11 may obviously be in the form of a disk, if the motor shaft does not pass through it. When the governor weight at an increase of speed of the motor makes a deflection, the eccentricity of the ring 11 will—as will readily be understood—be diminished, the obvious consequence of which is a diminution of the distance which the pump piston 8 is moved by the eccentric 11, 12. This arrangement thus

works analogously with the arrangement previously described. The impact to which the governing device is exposed at each functional movement of the pump piston is transferred to the governor weight, the inertia of which must therefore be so great, that the weight does not move out of its position of equilibrium.

In Fig. 7 is shown a device in which there are two governor weights 4^a and 4^b , of which only the one, 4^a , is connected with the other parts of the device. The weight 4^b is also fixed to the web of the fly wheel by means of a pivot. The two weights are connected with each other by means of a link 4^c , which has such a position that if the weight 4^a in consequence of an impact strives to move outward, this tendency is by means of the link 4^c and the weight 4^b transferred to the pivot of the latter weight and thereby entirely or partially counteracted. In a double motor the two governor weights 4^a and 4^b can work in conjunction each with a motive fluid pump.

Fig. 8 shows a modification of the device shown in Fig. 7. In this modification the link 4^c is omitted, and instead of the same each of the governor weights carries a round, rotatable disk 4^d , against which rests a prolongation of the other weight. The mode of action of this device is, as to the transfer of the tendency of the one weight to move outward to the pivot of the other weight, similar to the one of the device shown in Fig. 7.

Instead of acting on one pump piston only during a revolution the shoulder 7 can act

on two or more pump pistons, one or more of which can serve to force water into the working chamber or chambers of the motor. 40

Having now described our invention, what we claim as new and desire to secure by Letters Patent is:

1. A governing device for combustion motors, embodying therein a motor and a pump for supplying motive fluid thereto, a plurality of spring controlled weights carried by a rapidly moving part of the motor, means for operating said pump connected with said weights, and means for interconnecting said weights whereby the outward tendency of one weight occasioned by operation of the pump is transmitted in a substantially straight line to the other weight. 45

2. A governing device for combustion motors, embodying therein a motor and a pump for supplying motive fluid thereto, a pair of weights each pivotally mounted on the fly wheel of the motor, springs for limiting the centrifugal movement of said weights, means for actuating said pump connected with said weights, and a connection between said weights whereby the tendency of one weight to move as the result of actuation of said pump is transmitted in a substantially straight line to the pivot of the other weight and such tendency is thus counteracted. 55

In witness whereof we have hereunto set our hands in presence of two witnesses.

CARL ALRIK HULT.
OSCAR WALFRID HULT.
